US00D888591S

(12) **United States Design Patent** (10) **Patent No.:** **US D888,591 S**
(45) **Date of Patent:** **** Jun. 30, 2020**

(54) **HEIGHT GAUGE**

(71) Applicant: **TESA SA**, Renens (CH)

(72) Inventors: **Hervé Destraz**, Neyruz-sur-Moudon (CH); **Sébastien Granges**, Lausanne (CH); **Michel Rochat**, Lussy-sur-Morges (CH)

(73) Assignee: **TESA SARL**, Renens (CH)

(**) Term: **15 Years**

(21) Appl. No.: **35/506,473**

(22) Filed: **Sep. 27, 2018**

(80) **Hague Agreement Data**

Int. Filing Date: **Sep. 27, 2018**

Int. Reg. No.: **DM/200224**

Int. Reg. Date: **Sep. 27, 2018**

Int. Reg. Pub. Date: **Mar. 29, 2019**

(51) **LOC (12) Cl.** **10-02**

(52) **U.S. Cl.**

USPC **D10/70**

(58) **Field of Classification Search**

USPC **D10/70, 71, 73**

CPC **G01B 5/008; G01B 5/061; G01B 3/006; G01B 5/004**

See application file for complete search history.
